CLAIM

I claim the ornamental design for a candle lighter/snuffer, as shown and described.

DESCRIPTION

FIG. 1 is a perspective view of a candle lighter/snuffer showing my new design;

FIG. 2 is a perspective view thereof;

FIG. 3 is a side elevation view thereof;

FIG. 4 is a top plan view thereof;

FIG. 5 is a bottom plan view thereof; and,

FIG. 6 is a sectional view of the candle light/snuffer thereof taken along line 6—6 from FIG. 3.

The broken lines shown in FIG. 1 represent portions of the design that form no part of the claim.
